UNITED STATES PATENT OFFICE.

JAMES BUDD, OF SANDY HILL, NEW YORK.

IMPROVEMENT IN PUMPS.

Specification forming part of Letters Patent No. 35,077, dated April 29, 1862.

To all whom it may concern:

Be it known that I, JAMES BUDD, of Sandy Hill, in the county of Washington and State of New York, have invented a new and useful Improvement in Pumps, designed more especially for Fire-Engines; and I do hereby declare that the following is a full, clear, and exact description of the same, reference being had to the accompanying drawings, making a part of this specification, in which—

Figure 1 is a longitudinal vertical section of my invention, taken in the line $x x$; Fig. 2. Fig. 2 is a transverse vertical section of the same, taken in the line $y y$, Fig. 1.

Similar letters of reference indicate corresponding parts in the two figures.

The object of this invention is to obtain a pump by which water can be drawn simultaneously from two different fountains or reservoirs, or drawn from either separately, as desired, and also ejected simultaneously from two different nozzles or eduction-pipes, or from either separately, and at the same time not involve the necessity of any complicated arrangement of parts, but one which will admit of the piston being operated by a short stroke and a rapid movement.

To enable those skilled in the art to fully understand and construct my invention, I will proceed to describe it.

A represents the pump-cylinder, which is in a horizontal position, and B the piston, the rod C of which passes, as usual, through a stuffing-box, D, at one end of the cylinder. The piston B is formed of two parts, $a a'$, of cup form, in each of which a ball-valve, E, is placed, and which when closed cover openings $b b$ in the inner sides of the cups. The cups or parts $a a'$ of the piston are connected at a suitable distance apart by curved arms c, which project from a central tube, d, as shown in Fig. 1. F is the induction-pipe, which communicates with the cylinder A at the center of its lower side, and G is a retaining-valve, which is placed in a chamber, G', with which the induction-pipe F' communicates, as shown in Fig. 2.

On the upper part of the cylinder A there is placed a valve-chamber, H, which is divided into two compartments, $e e'$, by a vertical central partition, f, each compartment being pro-

vided with a ball-valve, g, both of which are shown in Fig. 1. The compartments $e e'$ communicate at their lower parts, respectively, with water-passages $h h'$, which are divided by a partition, i, and communicate with the ends of the cylinder A.

On the valve-chamber H there is placed an air-chamber, I, having a valve, J, at its lower part opening upward. To the upper end of the air-chamber I an eduction-pipe, K, is attached. The upper end of the pipe K communicates with a chamber, L, which has two nozzles, M M', connected with it, one at its upper end and the other at its lower end, and within the chamber L there is placed a valve, N, which has two seats, $j j'$, one being above and the other below the orifice of the pipe K. (See Fig. 1.) The stem O of the valve N passes through a stuffing-box, P, at the upper end of the chamber L, so that the valve N may be adjusted to fit in either seat j or j' , or be so adjusted as not to be in contact with either, in which position it is shown in Fig. 1 in dark shading.

Q is a pipe, which also serves as an induction-pipe and communicates with the chamber G', in which a valve, S, is placed, the seat k of which is above the valve G and lower end of the induction-pipe F'. The induction-pipe F is continued by connecting an additional length to the lower end of the chamber G'. The valve S is provided with a stem, T, which passes up through a stuffing-box, U, on the upper end of the chamber G', and has a nut, V, on its upper part, said nut being provided with two pendent arms, l l, which fit in a spiral groove or slot, m, in a cup-shaped flange or projection, W, on the top of chamber G'. (See Fig. 2.) The nut, with its arms and the spirally-grooved cup-shaped flange or projection, serves as a means for raising and lowering the valve S. Other devices, however, may be employed for the purpose.

The operation is as follows: The piston B may be operated by hand or other power, the length of the stroke of the piston being equal to the length of the space between the two parts $a a'$ of the same, so that the induction-pipe F will always communicate with the cylinder A between the two parts of the piston, as will be fully understood by referring to

Fig. 1. When the piston B is moving in the direction indicated by the arrow 1, the water in cylinder A in front of the piston is forced up through the passage h into the compartment e of the valve-chamber H, the valve g rising under the pressure of the water, and the latter passing up through or around valve J into the air-chamber I, and up through the education-pipe K into chamber L, from which, if the valve N be adjusted midway between its two seats j j' , the water will escape through both nozzles M M', and if the valve S in the chamber G' be adjusted down from its seat k the water will be drawn through both pipes F' Q into the pump-cylinder, as indicated by the arrow 2. When the piston B moves in the opposite direction, as indicated by the arrow 3, the water in the back part of the cylinder A, behind the piston B, which was drawn into it by the previous movement of the piston, is forced up through the passage h' into the chamber e' , and thence up through valve J into the air-chamber I and through the education-pipe K and out of the nozzles M M', the front part of the cylinder A being filled with water during this backward movement of the piston. If it should be desired to draw water through the pipe F' only, the valve S is drawn up against its seat k , as shown in red outline, Fig. 2, so as to cut off pipe Q from the chamber G', and in case it should be required to draw water through the pipe Q only valve S is lowered in chamber G', so that the lower end of its stem T will bear upon the upper end of the stem of valve G and keep the latter closed, and the water may be forced out of either of the nozzles M or M' by adjusting the valve N against the seat j or j' , which forms the communication between the nozzle to be cut off and the chamber L. The valve

N may be adjusted in the same way as valve S, or by other suitable means. By the construction of the piston B and its arrangement relatively with the induction-pipe F, as shown, the piston B may be operated with a short stroke and a very rapid movement—an important result in a pump designed for a fire-engine—and by having the two induction-pipes F' Q connected with the chamber G', provided with the valves G and S, arranged substantially as shown, to admit of the water being drawn through either or both pipes simultaneously, a great advantage is obtained, for the pump may be supplied from two fountains or reservoirs at different heights, the higher one being used until exhausted, and then the supply taken from the lower one, the change being made without the loss of time in shifting and adjusting hose, the valve S only requiring to be adjusted, which may be done in a moment of time. An equal advantage is also obtained by the arrangement of the two nozzles M M' and the valve N, by adjusting which two streams may be thrown from the pump, or one only from either nozzle.

Having thus described my invention, what I claim as new, and desire to secure by Letters Patent, is—

1. The two induction-pipes F' Q, in combination with the chamber G', provided with the valves G S, and all arranged substantially as and for the purpose set forth.
2. The combination and arrangement of the two nozzles M M', chamber L, and valve N, and education-pipe K, substantially as and for the purpose set forth.

JAMES BUDD.
